LIGHTER CONSTRUCTION

Alfred F. Reilly, North Attleboro, Mass., assignor
to Evans Case Company, North Attleboro,
Mass., a corporation of Massachusetts

Application January 20, 1936, Serial No. 59,822

12 Claims.

(Cl. 67—7)

This invention relates to lighters and more particularly to catalytic action lighters.

One of the objects of this invention is to provide a catalytic lighter which is simple and inexpensive in construction and thoroughly efficient and reliable in operation. Another object is to provide a lighter of the above nature which is sturdy and durable and which may be used over extended periods without the necessity of replacement of parts or of refueling. Another object is to provide a lighter of the above nature which is readily operable regardless of weather conditions. Another object is to provide a lighter of the above nature which is attractive in appearance and comparatively small in size though having ample fuel capacity. Other objects will be in part apparent and in part pointed out hereinafter.

The invention accordingly consists in the features of construction, combinations of elements, and arrangements of parts as will be exemplified in the structure to be hereinafter described and the scope of the application of which will be indicated in the following claims.

25 In the accompanying drawing in which is shown one of the various embodiments of my lighter,

Figure 1 is a vertical section of the lighter and cap with the cap removed; and

30 Figure 2 is an elevation of the lighter, partly in section, with the cap in place.

Similar reference characters refer to similar parts throughout the several views of the drawing.

35 In order that certain features of this invention may be more readily understood, it should be noted that pyrophoric lighters are notoriously complicated and, because of their relatively large number of moving parts, are subject to damage often necessitating repairs beyond the ability of the user. These lighters are also dependent for 40 operation upon a sparking material and a protruding wick both of which become consumed upon extended operation and both of which are not always easily replaced. It might 45 also be pointed out that many catalytic lighters are unsatisfactory due to the more or less constant exposure of the catalytic agent to the vaporized fuel which condenses upon the catalyst thus rendering it inactive until it has dried out.

50 Still other catalytic lighters provide indifferent ignition of a cigarette or the like because of the difficulty of drawing air through the fuel chamber. In addition the catalyst in many of these lighters becomes prematurely debilitated through

overexposure to vapor and the atmosphere. Another object of this invention is to rectify the above conditions in addition to many others.

Referring now to the drawing and to Figure 1 in particular, I provide a casing generally indicated at 10 which may be of any desirable shape or size and which may be formed of any suitable material such as metal or a phenolic condensation product. Casing 10 is preferably tubular, however, and preferably has an integral bottom 11 and an open top 12. The upper inner portion of casing 10 is preferably threaded as at 13 to threadably receive a bushing or the like generally indicated at 14. Bushing 14 comprises an annular shoulder 14a which seats on top 12 of 15 the casing and a reduced portion 14b which is suitably threaded for a purpose to be pointed out hereinafter. Extending through reduced portion 14b are a suitable number of air inlet ports 15 which provide communication between the atmosphere and the interior of casing 10.

A cap generally indicated at 16 (Figures 1 and 2) is provided with interior threads 16a (Figure 1) which threadably engage the threads on reduced portion 14b of bushing 14 and accordingly seal the interior of casing 10 from the atmosphere. Thus the lower portions of the side walls of cap 16 hermetically seal inlet ports 15 when the cap is threaded onto bushing 14.

Still referring to Figure 1, bushing 14 is preferably provided with concentric bores 17 and 18, bore 18 preferably being larger than bore 17 to provide an annular shoulder or seat 19. A substantially cup-shaped shell part 20 or the like is preferably force fitted within bore 18 and seats on shoulder 19 thus conveniently forming a top to casing 10. Shell 20 is provided with an opening 20a and in this opening I fix the upper or fuel vapor exit end 22a of a fuel vapor tube 22. Preferably fuel vapor tube 22 is substantially rigid and, when in its assembled position within casing 10, is immovable therefrom, this type of tube being provided for a purpose pointed out hereinafter. Tube 22 extends downwardly through casing 10 and terminates in a fuel vapor admission end 22b spaced from bottom 11 of the casing. Admission end 22b of tube 22 is preferably provided with threads 22c which threadably receive a retaining washer 23.

Disposed between retaining washer 23 (Figure 50 1) and the bottom of shell 20, I provide a mass of absorbent material generally indicated at 24 which may conveniently be in the form of a plurality of felt washers 24a disposed about tube 22 and held in place thereon by retaining washer 23. 55

It may now be seen that felt washers 24a are maintained in constant alignment due to the rigidity of vapor tube 22 thus avoiding any possibility of clogging of the vapor channel.

Preferably the diameter of absorbent material 24 is substantially smaller than the inner diameters of casing 10 and bore 17 of bushing 14 to provide an annular space 25 between the absorbent material and the casing.

It may now be seen that retaining washer 23 through its association with tube 22 maintains the bottommost of washers 24a a constant distance from the bottom of casing 10, thus assuring at all times free passage of fuel vapor from space 25 to vapor tube 22. Also by providing annular space 25 between the absorbent material and the casing, the fresh air admitted through port 18 and flowing down through space 25 contacts or wipes against the outer peripheries 24b of washers 24a to assure a concentration of fuel vapor in the air. Thus a passageway for gases is formed between inlet ports 15 and exit end 22a of tube 22, as indicated by the arrows (Figure 1), by way of space 25 and tube 22 for a purpose to be pointed out hereinafter.

Slidably disposed in shell 20 I provide a sleeve member generally indicated at 21, this sleeve member having a flange 21a formed around the bottom thereof. The top edge 20b of shell 20 is inturned and this edge provides an abutment against which flange 21a of sleeve 21 abuts to prevent dissociation of the sleeve from the shell. Preferably sleeve 21 is substantially deeper than shell 20 and is in telescopic relation thereto.

A suitable number of holes 21c are preferably formed in the bottom 21b of sleeve 21, and these holes are communicable with tube 22 while the lighter is in operation. Preferably holes 21c are arranged adjacent the periphery of bottom 21b which provides a supporting surface for a catalyst container 26, preferably freely disposed within sleeve 21. In order to maintain container 26 in its proper operative position and centered with respect to holes 21c so as not to cover the holes, I have provided a spacing ring 27 or the like which conveniently takes the form of a corrugated wire ring. A piece of catalytic material 28 is disposed within container 26 and may be held therein by frictional contact of the adjacent peripheries of the material and the container. Preferably the top of catalyst 28 is provided with corrugations or ridges 28a, the catalyst preferably being of substantially the same depth as container 26. Preferably container 26 is imperforate. Hence the only exposed portion of catalyst 28 is the top surface thereof, this limited exposure being effected for a definite purpose pointed out hereinafter.

Preferably force fitted in the top of sleeve 21 (Figure 1) is a bushing or cigarette receiver 29 whose bore is preferably bell shaped. Bushing 29 is preferably composed of a translucent, fire-proof substance such as pyrex glass for example. The lower portion 29a of the bore of the bushing is preferably substantially vertical and the diameter of this portion of the bushing is preferably substantially equal to the diameter of a standard cigarette so as to provide a snug fit for a substantial portion of one end of the cigarette when it is introduced into the bushing and against catalyst 28 for lighting. This snug fit greatly impedes the passage of air or vapor between the cigarette and bushing 29, this being advantageous as will be more clearly pointed out hereinafter. However, due to the greater diameter of the

upper portion of bushing 29 a cigarette may be conveniently inserted therein. A suitable number of channels or passages 29b are formed about the bottom of bushing 29 and these passages communicate with inlet ports 21c in the bottom of sleeve 21 by way of the space between the wall of sleeve 21 and the wall of catalyst container 26. Bushing 29 is preferably so dimensioned that its bottom portion 29c (Figure 2) engages the upper edge 26a of container 26 thus securing the container in its proper operative position.

It may now be seen that a passageway for the inlet of air and the outlet of vaporized fuel is provided by way of inlet ports 15 in bushing 14, space 25 in casing 10, tube 22, the interior of shell 20, inlet ports 21c in sleeve 21, sleeve 21, and passages 29b in bushing 29. It will also be seen that vaporized fuel drawn through passage 29b, as when a cigarette is puffed, passes only over the top surface of catalyst 28 thus assuring the long life of the catalyst and concentrating the heat at the point where it is needed to light the cigarette. Furthermore, as the end of the cigarette fits snugly within portion 29a of bushing 29, substantially no air is drawn in over the top of catalyst 28 to weaken the concentration of fuel vapor.

Secured in any suitable manner to the bottom of shell 20 is a spring 30 preferably conical in form which presses upwardly against the bottom of sleeve 21 thus constantly urging the sleeve into its uppermost position where flange 21a abuts in-turned shell edge 20b to limit further movement. It should be noted that by disposing spring 30 in the bottom of shell 20 so that its expansion reacts against the bottom of sleeve 21, there is no tendency of the spring to force absorbent material 24 out of the casing should the several parts of the lighter become worn after extended use. Preferably I provide a gasket 32 of rubber or the like secured in any suitable manner to the bottom of shell 20, this gasket having a hole 32a therein in registry with exit end 22a of conduit 22. Sleeve 21 has secured thereto in any suitable manner a needle valve 31 which, when sleeve 21 is depressed, enters hole 32a in gasket 32 and seats on the gasket to seal hermetically the fuel vapor exit end 22a of tube 22.

As is more clearly shown in Figure 2, cap 16 is preferably so dimensioned that, as it is screwed down over the upper threaded portion 14b of bushing 14, the upper inner surface 16b of the top of the cap engages the top edge 21d of sleeve 21 thus forcing sleeve 21 downwardly against the bias of spring 30 so that the tapered end of valve 31 enters the hole in gasket 32 thus pressing the gasket against the exit end 22a of tube 22 to seal the tube and prevent the flow of vaporized fuel therefrom into the vicinity of catalyst 28. Hence the amount of vaporized fuel which is trapped and which may come into contact with catalyst 28 is so slight that, in the event of condensation thereof, there is not sufficient condensate to affect adversely the subsequent operation of the lighter. The remainder of the fuel which has become vaporized during the operation of the lighter immediately prior to the screwing down of the cap on the casing is trapped within tube 22 and space 25 wherein its condensation has no effect on catalyst 28. It will also be seen that air inlet ports 15 are completely sealed from the atmosphere and because of the tight fit afforded by the respective threads on reduced portion 14b of bushing 14 and cap 16, it is practically impossible for vaporized fuel to escape. It should also be noted that when

cap 16 is in place, its surface 16b engages top edge 21d of sleeve 21 so firmly that catalyst 28 is effectively sealed from the atmosphere. I prefer the threaded engagement between cap 16 and bushing 14 as such an engagement effectively precludes displacement of the cap by spring 30 after the several parts of the lighter have become so worn through extended use that the spring would force the cap out of its seated position were there no more than a sliding fit holding the cap in place on the casing. Thus the catalyst is completely segregated from both fuel vapor and the atmosphere and will accordingly have a much longer period of usefulness than if it were not so completely protected.

In operation cap 16 is unscrewed from its seat on bushing 14 and the end of a cigarette is placed within bushing 29 against catalyst 28. Upon the cigarette being puffed, air enters casing 18 by way of inlet ports 15, thence passes through space 25 and contacts absorbent material 24 during which it combines with fuel vapor. The vaporized fuel then passes along the bottom of casing 18 and up through tube 22 through shell 26, ports 21c and passages 29b and over the top of catalyst 28. By reason of the catalytic action of catalyst 28, the catalyst glows and provides a sufficient amount of heat to light the cigarette. Thereafter cap 16 is screwed down on bushing 14 thus forcing valve 31 into its seat on gasket 32 to close vapor exit end 22a of tube 22; the lower portions of cap 16 close air inlet ports 15 when the cap is fully in place.

Accordingly it will be seen that I have provided a catalytic lighter in which the several objects mentioned hereinabove as well as many others are achieved in a thoroughly practical and efficient manner.

As many possible embodiments may be made of the above invention and as many changes might be made in the embodiment above set forth, it is to be understood that all matter hereinbefore set forth, or shown in the accompanying drawing, is to be interpreted as illustrative and not in a limiting sense.

I claim:

1. In a lighter, in combination, means forming a container adapted to receive a volatile fuel, a part secured to said container and having a fuel vapor port therein, a fuel vapor conduit disposed in said container and having its vapor exit end secured to said part in communication with said port, means including a catalytic member movably disposed in said part, and a needle valve on the underside of said last mentioned means cooperable with a rubber gasket surrounding said port and adapted to seal said port when said last-mentioned means is moved in one direction.

2. In a lighter, in combination, means forming a casing for a volatile fuel, a part secured in said casing and having a fuel vapor port therein, a fuel vapor conduit in said container having a vapor exit in communication with said port, a closed sleeve member disposed for limited movement in said part, the bottom of said sleeve member and the bottom of said part forming a chamber in communication with the exit of said vapor conduit and said fuel vapor port, a catalyst container mounted in said sleeve member, the walls of said container being spaced from the walls of said sleeve member to form a vapor passage, the bottom of said sleeve member having an opening therein to establish communication between said passage and said chamber, a catalyst in said container, the height of said catalyst be-

ing substantially equal to the height of said container whereby fuel vapor flowing from said casing through said conduit, said chamber and said passage comes into contact with the upper surface only of said catalyst, and means associated with said sleeve member for sealing said exit end of said conduit when said sleeve member is at one limit of its movement in said part, the volume of said chamber being greatly reduced when said tube is sealed whereby the amount of vapor trapped in engagement with said catalyst is insufficient to affect the subsequent operation thereof.

3. In a lighter, in combination, means forming a casing adapted to receive a volatile fuel, a part secured in the upper portion of said casing and having a port therein, an elongated conduit having a fuel vapor admission end and a fuel vapor exit end, said conduit being secured to said part, so that said port and said fuel vapor exit end are in communication, and means including a catalytic member movably disposed in said part, and a needle valve on the underside of said last mentioned means cooperable with a rubber gasket surrounding said port adapted to seal said port and segregate said catalytic member from substantially all fuel vapor when said last-mentioned means is in one position of its movement.

4. In a lighter, in combination, means forming a casing adapted to receive a volatile fuel, a substantially cup-shaped part secured in the upper portion of said casing, an elongated fuel vapor conduit disposed in said casing and secured to said cup-shaped part and in communication with the interior thereof, said conduit having a fuel vapor admission end and a fuel vapor exit end, a plurality of absorbent washers disposed about said conduit, said washers forming an absorbent column whose exterior surface is spaced from the interior surface of said casing, a catalytic member associated with said cup-shaped part, said catalytic member being sealed on the bottom and sides and open at the top, and a needle valve on the underside of said cup-shaped part cooperable with the rubber gasket surrounding the exit end of said conduit for sealing said exit end of said conduit to substantially completely segregate said catalytic member from fuel vapor.

5. In a lighter, in combination, means forming a casing adapted to receive a volatile fuel, an elongated fuel vapor conduit immovably disposed in said casing, a catalytic member movably associated with the upper portion of said casing, said catalytic member being substantially adjacent the fuel vapor exit end of said conduit, means for sealing said exit end of said conduit whereby said catalytic member is substantially completely segregated from fuel vapor when in one position of its movement, and means for conducting fuel vapor to the top surface only of said catalytic member when said catalytic member is in another position of its movement.

6. In a lighter, in combination, means forming a casing adapted to receive a volatile fuel, an elongated fuel vapor conduit immovably disposed in said casing, a catalytic member movably associated with the upper portion of said casing, said catalytic member being substantially adjacent the fuel vapor exit end of said conduit, means for sealing said exit end of said conduit whereby said catalytic member is substantially completely segregated from fuel vapor when in one position of its movement, means for conducting fuel vapor to the top surface only of said catalytic member when said catalytic member is in another position

of its movement, and spring means adapted to bias said catalytic member toward said last-mentioned position.

7. In a lighter, in combination, means forming a casing adapted to receive a volatile fuel, a part secured in the upper portion of said casing, a fuel vapor conduit having a fuel vapor admission end and a fuel vapor exit end, said conduit being secured to said part whereby said fuel vapor exit end is in communication with the interior of said part, a member reciprocably disposed in said part, spring means disposed between said part and said member and adapted to bias said member upwardly, the interior of said member being in communication with the interior of said part whereby said fuel vapor flowing from said exit end flows through said part and into said member, a catalyst disposed in said member in the path of fuel vapor, means for urging said member downwardly against the action of said spring, and means associated with said member for sealing the vapor exit end of said conduit when said member is forced downwardly.

8. In a catalytic lighter, a body comprising a container for volatile fuel and a chamber adjacent said container having an opening in the bottom wall communicating with said container, said container having an air inlet port, a movable element in said chamber including a catalyst, a needle valve on the underside of said movable element cooperable with a rubber gasket surrounding said opening to close said opening on movement of said element towards said container, and a cap detachably securable to said body to seal said air inlet port and engageable with said element to move said element towards said container.

9. In a catalytic lighter, a body including a container for volatile fuel and a chamber adjacent said container having an opening in the bottom wall communicating with said container, said container having an air inlet port, a mov-

able element in said chamber including a catalyst, a needle valve on the underside of said movable element cooperable with a rubber gasket surrounding said opening to close said opening on movement of said element towards said container, means resiliently urging said element away from said container, and a cap detachably securable to said body to seal said air inlet port and engageable with said element to move said element towards said container.

10. In a catalytic lighter, a container adapted to receive a volatile fuel and having a fuel vapor flow passage, a chamber adjacent said container in communication with said flow passage, a catalyst element in said chamber, said catalyst element being sealed on the bottom and sides and open at the top, and a flow conduit associated with said chamber for directing fuel vapor from said chamber to the upper open surface of said catalyst element.

11. In a catalytic lighter, a container adapted to receive a volatile fuel, a chamber adjacent said container having an opening in the bottom wall thereof communicating with said container, an element reciprocable in said chamber containing a catalyst, and a needle valve on the underside of said element cooperable with the rubber gasket surrounding the opening in the bottom wall of said container for closing said opening.

12. In a catalytic lighter, a container adapted to receive a volatile fuel and having a vertical fuel vapor flow passage, a chamber adjacent said container in communication with said flow passage, means comprising a catalyst sealed on the bottom and sides and open at the top, movable in said chamber to seal said vertical passage, said means including a needle valve on the underside of said catalyst cooperable with a rubber gasket surrounding the opening to said vertical passage, and resilient means in said chamber urging said movable means away from said container.

ALFRED F. REILLY.
